(57) CLAIM

The ornamental design for a waterproof storage enclosure, as shown and described.

DESCRIPTION

FIG. 1 is a front perspective view of a waterproof storage enclosure showing my new design;

FIG. 2 is a right elevation view of the invention illustrated in FIG. 1;

FIG. 3 is a left elevation view of the invention illustrated in FIG. 1;

FIG. 4 is a top plan view of the invention illustrated in FIG. 1;

FIG. 5 is front elevation view of the invention illustrated in FIG. 1;

FIG. 6 is a rear elevation view of the invention illustrated in FIG. 1;

FIG. 7 is a bottom plan view of the invention illustrated in FIG. 1; and,

FIG. 8 is a front perspective view of the invention illustrated in FIG. 1 shown in an open position.
